UNITED STATES PATENT OFFICE.

SAMUEL T. ADAMS, OF NEW BEDFORD, MASSACHUSETTS, ASSIGNOR TO THE PAIRPOINT MANUFACTURING COMPANY, OF SAME PLACE.

DESIGN FOR A SPOON.

SPECIFICATION forming part of Design No. 21,106, dated October 13, 1891.

Application filed July 25, 1891. Serial No. 400,772. Term of patent 14 years.

To all whom it may concern:

Be it known that I, SAMUEL T. ADAMS, of New Bedford, in the county of Bristol and State of Massachusetts, have invented and produced a new and original Design for Handles for Table-Ware, of which the following is a specification, reference being had to the accompanying drawing, forming part hereof.

The figure is a plan of a handle (for a spoon) containing my design.

My design consists in the hereinafter-described outline and ornamentation.

In the drawing showing my design the butt-end edge a of the handle is curved outwardly from each corner a' , formed by the junction of the butt-end edge a and side edges a^2 of the handle. Each side edge a^2 is curved inwardly at a^3 from its corner a' toward the inner end of the handle, then outwardly at a^4 , and then inwardly at a^5 . The margin at the butt-end edge a has a series of curved ridges b terminating in bosses b' , and the margins next the side edges a^2 from the corners a' to about midway the outward curves a^4 have con-

ventionalized feathers b^2 extending from the edges a^2 inwardly. From the termination of this feathered work to the termination of the inward curves a^5 these margins have a series of bosses b^3 arranged in a curved line. At the termination of the inward curves a^5 the handle has a series of longitudinal ridges b^4 extending from edge to edge of the handle. The feathered work b^2 and balls b^3 and sides b^4 inclose a plain ovalish-shaped surface B .

I claim—

The design for a spoon as herein shown and described, the same consisting of the outwardly-curved butt-end edge a and sides a^2 , each curved inwardly at a^3 , then outwardly at a^4 , and then inwardly at a^5 , a plain ovalish surface B , surrounded by feather-work b^2 , boss-work b^3 , and ridge-work b^4 , the butt-end margin of the handle having the curved ridges b terminating in bosses b' , all as shown.

SAMUEL T. ADAMS.
